INVENTOR

Joseph Bull Little,
by J. R. Little,
his Attorney.

UNITED STATES PATENT OFFICE.

JOSEPH BULL LITTLE, OF WINNIPEG, MANITOBA, CANADA.

SAFETY WATER-GAGE.

SPECIFICATION forming part of Letters Patent No. 363,071, dated May 17, 1887.

Application filed December 23, 1886. Serial No. 292,344. (No model.)

To all whom it may concern:

Be it known that I, JOSEPH BULL LITTLE, a subject of the Queen of Great Britain, residing at Winnipeg, in the Province of Manitoba 5 and Dominion of Canada, have invented certain new and useful Improvements in Indicators or Gages for Steam-Boilers; and I do hereby declare that the following is a full, clear, and exact description of the invention, 10 which will enable others skilled in the art to which it appertains to make and use the same.

My invention relates to indicators or gages for steam-boilers, and more particularly to that 15 class in which valves are normally held in an open position and adapted to be closed should the glass sight-tube be broken.

The object of the invention is to provide improved means for supporting the valves from their seats and lowering them should said 20 glass sight-tube be broken.

A further object of the invention is to improve the construction of devices of this character and to make their operation simple and thoroughly effective.

25 The invention consists in the combination, with a glass sight-tube and its mountings, said mountings having valve-seats, of valves to close said seats and a rod composed of a series of sections connected by links having each 30 a laterally-extending arm or arms.

The invention further consists in the features of construction and combination of parts hereinafter fully described, and pointed out in the claims.

35 In the drawings, Figure 1 is a vertical section of a glass sight-tube and its mountings, illustrating the valves and my improvement applied thereto. Fig. 2 is an enlarged detail view of the jointed rod detached, and Fig. 3 40 is a detail view of one of the valves.

Corresponding parts in the several figures are denoted by the same letters of reference.

Referring to the drawings, A A' represent the mountings for receiving the upper and 45 lower ends of the glass gage-tube B, said mountings being provided with water-tight joints a.

C C' represent, respectively, the inlet and outlet tubes, which are each preferably provided with a stop-cock. (Not shown.)

50 D represents valve-seats, which are formed

in the mountings A A', and which are adapted to be closed, when the sight-tube is broken, by valves E E', which valves are normally held from contact with the seats, thus allowing a free circulation through the sight-tube. 55 In the inner ends of the valves E E' are formed openings or seats g, which are adapted to receive the ends of a rod, F, for supporting the valves from contact with the valve-seats. This rod or support consists of a series of sections, e, of any desired or suitable number, and connected by links G, having bifurcated ends, in which the sections are pivoted.

H represents arms which project laterally from each side of the link, and are adapted to 65 bear against the interior face of the sight-tube. These arms may be formed integral with the links, or they may consist each of a single piece of metal extending through openings in the links, as in the present instance.

70 It will be observed that should the glass sight-tube become broken the jointed rod will in its efforts to collapse lower the upper valve to its seat and raise the lower valve up against its seat. The lower valve, E', has a supplemental valve, H', to engage a seat, I, in the lower end of the mounting A', which seat communicates with a passage, h, leading to the exterior of the device. When the glass tube is intact this supplemental valve will be held 75 to its seat and the passage h closed; but when the sight-tube is broken the supplemental valve is raised from its seat I, and communication between the boiler and the passage h thus established, so that the valve E' is simultaneously raised up against its seat D and closed.

80 The device above described is simple in its construction, effective in its operation, and at the same time cheap to manufacture and 85 strong and durable.

90 Having thus fully described my invention, I claim—

1. The combination, with a glass tube and its mountings, said mountings having valve-seats, of valves to close said seats and a rod for supporting said valves from their seats, said rod consisting of a series of sections connected by links, each having a laterally-extending arm or arms, substantially as described. 95 100

2. The combination, with a glass tube and its mountings, said mountings having valve-seats, of valves to close said seats, a jointed rod connected to said valve, said rod comprising a series of sections connected by links having bifurcated ends, in which said sections are pivoted, and arms passing through openings in said links, substantially as set forth.

3. The combination, with a glass sight-piece and its mountings having valve-seats, of valves and a rod connecting the valves for normally

holding them in an open position, one of said valves being provided with a supplemental valve normally engaging a seat in one of the mountings, substantially as set forth.

In testimony whereof I affix my signature in presence of two witnesses.

JOSEPH BULL LITTLE.

Witnesses:

NEIL KEITH,
EDWARD BULL.
